UNITED STATES PATENT OFFICE

98,096

DESIGN FOR A BEVERAGE COOLER

George V. Steffens, Clayton, Mo.

Application October 17, 1935, Serial No. 59,097

Term of patent 14 years

To all whom it may concern:

Be it known that I, George V. Steffens, a citizen of the United States, residing at the city of Clayton, in the county of St. Louis and State of Missouri, have invented a new, original, and ornamental Design for a Beverage Cooler, of which the following is a specification, reference being had to the accompanying drawing, forming a part thereof.

The figure is a perspective view of a beverage cooler showing my new design.

The two elongated sides of the beverage cooler are of the same design. The end wall of the beverage cooler opposite from that shown in the drawing is plain.

I claim:

The ornamental design for a beverage cooler as shown and described.

GEORGE V. STEFFENS.
